(57) **CLAIM**

The ornamental design for a razor handle, as shown and described.

DESCRIPTION

FIG 1 is a perspective view of the razor handle showing the new design;

FIG. 2 is a front view thereof;

FIG. 3 is a rear thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate a portion of the razor handle and form no part of the claimed design.
